UNITED STATES PATENT OFFICE.

CHARLES DOERING, JR., OF CHICAGO, ILLINOIS.

DESIGN FOR A DISPLAY-CABINET FOR FISH AND OTHER FOODS.

45,413.

Specification for Design.

Patented Mar. 17, 1914.

Application filed October 20, 1913. Serial No. 796,348. Term of patent 7 years.

To all whom it may concern:

Be it known that I, CHARLES DOERING, Jr., a citizen of the United States, and residing in the city of Chicago, in the county of Cook and State of Illinois, have invented a certain new, original, and ornamental Design for Display-Cabinets for Fish and other Foods, of which the following is a specification, reference being had to the accompanying drawing, which forms a part of my specification, and in which the figure disclosing the invention consists of a perspective view of a display-cabinet for fish or other foods, the cabinet being shown in closed position and as the same is set up ready for use.

By referring to the drawing it will readily be seen that I have produced a design which is both new and original and which possesses certain ornamental features not heretofore found.

I claim—

The ornamental design for a display cabinet for fish and other foods, substantially as shown.

CHARLES DOERING, JR.
